UNITED STATES PATENT OFFICE.

LELAND S. HAMER, OF FULLERTON, CALIFORNIA.

PUMP.

Application filed March 10, 1925. Serial No. 14,363.

This invention relates to a construction for pumps of the cylinder and piston type and has particular reference to a cylinder construction for pumps, and the like.

5 Pump cylinders and cylinders in various other like mechanisms are usually provided with removable liners adapted to be removed from time to time for purpose of repair or replacement. These liners are usually made 10 to fit tightly into the bore of the cylinder casting by packing arranged between a shoulder in the casting and a shoulder on the liner. The liner is held against longitudinal movement relative to the cylinder casting 15 between the packing and a suitable member carried by the outer cylinder head. After a liner of this kind has been arranged in place and the pump operated for a time the liner comes loose and it is necessary to 20 tighten it by operation of the part carried by the cylinder head. In practice the liner is tightened from time to time during the operation of the pump until the packing becomes very tight. When it is desired to 25 move one of these liners it is usually necessary to apply special tools or devices to them as the packing being highly compressed holds the liner very tight.

It is an object of my invention to provide 30 a construction whereby a liner may be applied to a cylinder so that it is secure and will remain tight upon once being properly set.

Another object of my invention is to provide 35 a construction of the character described involving means for securing a liner in place without making it difficult to remove.

It is another object of this invention to 40 provide a construction of the character described in which the liner, that is, the part which actually carries the piston is in the form of a straight uniformly shaped cylinder and does not involve or include shoulders or projections such as are common to 45 pump liners.

Another object of this invention is to provide 50 a construction of the character described in which liners of various sizes may be arranged in the cylinder in a particularly simple and inexpensive manner.

The various objects and features of the 55 invention will be best and more fully understood from the following detailed description of a typical form and application of the

invention throughout which description reference is had to the accompanying drawings in which

Fig. 1 is a longitudinal detailed sectional view of a pump embodying the construction 60 provided by this invention.

Fig. 2 is an enlarged detailed sectional view of the pump cylinder showing the liner mounted therein in a manner provided by 65 this invention.

Fig. 3 is a transverse sectional view taken as indicated by line 3-3 on Fig. 2.

Fig. 4 is a detailed transverse sectional view taken as indicated by line 4-4 on Fig. 2. 70

My invention is applicable generally to cylinder and piston mechanisms in which it is desired to provide the cylinder with a liner. I have throughout this disclosure made particular reference to the invention 75 as applied to pumps as such devices serve well to illustrate the utility of the invention and the manner in which it may be employed practically. It is to be understood that I do not wish the scope or range of 80 application of the invention to be construed as limited to the specific details and application herein set forth.

In the drawings I have illustrated my invention as applied to the cylinder of a pump 85 of the type known as a slush pump.

The pump includes, generally, a cylinder 10, a valve chest 11, inner and outer cylinder heads 12 and 13, respectively, a piston rod 14 extending into the cylinder through a packing gland 15 in the inner head 12, a piston 16 carried by the rod within the cylinder and various other parts common to mechanisms of this character.

My invention provides, generally, a cylinder liner 17 to carry the piston 16 and a carrier 18 which holds the liner 17 and supports it in the cylinder 10. The liner 17 in accordance with my invention is a straight cylindrical liner uniform in size, both inside 100 and out, throughout its length.

The carrier 18 provided by my invention comprises a body 20 and a head 21. The body 20 is cylindrical in form and is adapted to slidably fit into the cylinder 10. The 105 cylinder 10 in accordance with constructions usual to pumps is provided at its outer end with an enlarged portion 22 which forms an outwardly facing shoulder 23, which serves as an abutment for the packing in the 110

usual liner mounting. In accordance with my present invention the body 20 of the liner carrier is somewhat shorter than the cylinder 10 and is provided at its outer end 5 with an enlargement or projection 24. The body is arranged into the cylinder through its outer end until the projection 24 engages the shoulder 23 at which time the inner end of the body is at the inner end of the cylinder.

10 The head 21 of the liner carrier is annular in form being in the form of a ring adapted to slidably fit the enlarged part 22 of the cylinder and to be arranged in the cylinder 15 after the body has been arranged in place.

Means is provided for holding the body 20 and head 21 in the proper relation, which means may comprise a plurality of studs 25 projecting from the outer end of the head, 20 or screws 50 may be carried by the cylinder head 13 to engage the head 21 in position. The openings 26 in the head slidably pass the studs 25 so that the head is movable relative to the body and can be clamped toward 25 the body by tightening up the nuts 27 at the outer end of the studs. The screws 50 are screw threaded through the cylinder head so that they can be tightened against the head 21 to force it toward the body 20. The 30 liner 17 is carried by or between inwardly extending flanges or projections 30 and 31 on the body 20 and head 21, respectively. The projection 30 is at the extreme inner end of the body while the projection 31 is at the extreme outer end of the head. In the case of 35 a comparatively large liner that is a liner only slightly smaller in diameter than the cylinder, it may be arranged in the carrier so that its ends are directly engaged by the 40 projections 30 and 31, however, in the case of liners substantially smaller than the cylinder 10, I provide spacer-rings 33 which fit the body and head to be engaged by the 45 projections 30 and 31. The spacer rings are provided with projections or parts 34 which engage the ends of the liner as clearly shown in Fig. 2 of the drawings. With this construction the body and head may be made of a standard size to fit the cylinder and 50 spacer-rings 33 may be provided for mounting any size liner in the carrier, it being obvious that the proportion of the spacer-rings may be varied to suit a liner of any size. The liner 17 being arranged between the 55 projections 30 and 31 or between the spacer-rings 33 engaged by the projections 30 and 31, the nuts 27 are applied to the studs 25 at the outer end of the head and are tightened onto the studs until the liner is tightly 60 clamped or held between the body and head.

The packing means provided by my invention for making a fluid tight connection between the liner and cylinder includes a body of packing 40 arranged in the enlarged part 65 22 of the cylinder between the outer end of

the body 20 and the inner end of the head 21.

The body of packing is proportioned so that it is compressed sufficiently to make the desired connection between the liner and cylinder upon the body and head being 70 pressed together to hold the liner. When the carrier is holding a liner sufficiently large to be directly engaged by the projections 30 and 31 the body of packing 40 may be properly held directly by the ends of the 75 body and head, however, when the liner is of such diameter to require spacer-rings 33 I may provide packing operating rings 42 at the outer end of the body 20 and inner end of head 21, which rings are proportioned 80 to fit closely to the exterior of the liner and to the interior of the cylinder and thereby properly hold the packing as shown in Fig. 2 of the drawings. The rings 42 and body of packing 40 are of course provided with 85 openings to properly pass the studs 25.

In employing the construction provided by this invention the body 20 is first slid into place in the cylinder until its projection 24 is in seated engagement with the shoulder 23 in the cylinder. The liner 17 may then be arranged in the body together with a spacer ring 33 if circumstances require the packing 40, and if necessary the packing operating rings 42 may be arranged in place. The 90 head 21 is then placed in the outer end of the cylinder on the studs 25, if they are employed together with a suitable spacer-ring, if circumstances require, whereupon the nuts 27 may be applied to the studs and tightened 100 until the packing is properly compressed and the liner tightly held between the body and head as hereinabove described. With the carrier and liner thus in place in the cylinder the head 13 of the pump cylinder may be applied to the end of the cylinder and the screws 50 provided in the head may be actuated to engage and hold the carrier and liner in place. In the particular construction shown in the drawings there is a plurality of 105 screws 50 carried by the cylinder head 13, which screws are located in the head so that they can be tightened against the outer end of the head 21 in the manner illustrated in Fig. 1 of the drawings. With the various 110 parts thus arranged in place the liner 17, body 20 and head 21 form a rigid construction which is positively prevented from moving inwardly in the cylinder by the interengagement of the projection 24 and shoulder 23 and is positively prevented from moving outward in the cylinder by the screws 50 engaging the outer end of the head 21. The 115 packing 40 being properly proportioned is compressed sufficiently to insure a fluid tight 120 connection between the liner and cylinder but is not made so tight as to bind the liner in the cylinder so that its removal is difficult. When it is desired to remove the liner for 125 purpose of repair or replacement the cylin- 130

der head 13 may be removed whereupon the end 21 of the carrier may be released by removal of the nuts 27 allowing the liner and packing and also the body 20 of the carrier 5 to be easily slid out of the cylinder.

In practice, I may eliminate the studs 25 and employ the screws 50 to clamp or hold the parts of the liner carrier together and also to hold the entire construction in place 10 in the cylinder.

Having described only a typical preferred form of my invention I do not wish to limit myself to the specific details set forth, but 15 wish to reserve to myself any changes or variations that may appear to those skilled in the art or fall within the scope of the following claims:

Having described my invention, I claim:

1. A construction to be arranged in a cylinder having a shoulder, a liner, and a carrier 20 for mounting the liner in the cylinder including two parts adapted to clamp the liner between them, the carrier having a projection to directly engage the shoulder, said parts having a space between them to hold packing so that it engages the cylinder and liner.

2. A construction to be arranged in a cylinder having a shoulder, a liner, and a carrier 30 for the liner including two parts having internal projections to engage the ends of the liner, one part having an external projection to engage the shoulder.

3. A construction to be arranged in a cylinder having a shoulder, a liner, and a carrier for the liner, including two parts each having a projection and spacers held by the projections and engaging the ends of the liner.

4. In combination, a cylinder, having a 40 shoulder, a liner, a carrier for the liner including two parts, one a body for holding one end of the liner, arranged in the cylinder and having a part engaging the shoulder and the other a head for holding the other end of liner, packing arranged in the cylinder between the body and head, and means 45 for holding the parts of the carrier in posi-

tion to hold the liner and in place in the cylinder.

5. In combination, a cylinder, having a 50 shoulder, a liner, a carrier for the liner including two parts, one a body for holding one end of the liner, arranged in the cylinder and having a part engaging the shoulder and the other a head for holding the other end of liner, packing arranged in the cylinder between the body and head, and a single means for holding the parts of the carrier in position to hold the liner and in place in the cylinder. 60

6. In combination, a cylinder, having a shoulder, a liner, a carrier for the liner including two parts, one a body for holding one end of the liner, arranged in the cylinder and having a part engaging the shoulder and the other a head for holding the other end of liner, packing arranged in the cylinder between the body and head, and means for holding the parts of the carrier in position to hold the liner and in place in the cylinder 70 said means including a part carried by the cylinder head to engage the head of the carrier and clamp it toward the body of the carrier.

7. In combination a cylinder having an 75 internal shoulder facing its outer end, a liner, a carrier for mounting the liner in the cylinder including a body arranged in the inner portion of the cylinder having an external projection engaging the shoulder 80 in the cylinder and having an internal projection at its inner end to hold the liner and a head extending into the outer part of the cylinder having an internal projection to hold the liner, packing arranged in the cylinder around the liner between the body and head, and a screw carried by the head of the cylinder for clamping the head of the carrier toward the body. 85

In witness that I claim the foregoing I 90 have hereunto subscribed my name this 23rd day of Feb. 1925.

LELAND S. HAMER.
